UNITED STATES PATENT OFFICE.

ERNEST J. DERAGON, OF FITCHBURG, MASSACHUSETTS.

CLOTHES-HANGER.

SPECIFICATION forming part of Letters Patent No. 605,633, dated June 14, 1898.

Application filed July 26, 1897. Serial No. 645,973. (No model.)

To all whom it may concern:

Be it known that I, ERNEST J. DERAGON, of Fitchburg, in the county of Worcester and State of Massachusetts, have invented certain new and useful Improvements in Clothes-Hangers, of which the following is a specification.

This invention has for its object to provide a clothes-hanger of simple and durable construction which shall combine compactness of form with large holding capacity.

The invention consists of certain features of construction and relative arrangement of parts, all as fully illustrated upon the drawings and now to be described in detail and then to be particularly pointed out in the claims hereto appended.

Of the drawings, Figure 1 represents a top view of a clothes-hanger embodying my invention. Fig. 2 represents a section on line 2 of Fig. 1. Fig. 3 represents a perspective view of the holder or fixed part of the hanger.

The same letters and figures of reference indicate like parts in all of the figures.

In the drawings, *a* represents a plate, which is or may be made of cast-iron and is adapted to be attached to a wall or other fixed support, screw-holes *a'* being formed in said plate. *a²* *a³* represent flanges formed on the front side of the plate *a*. The upper flange *a²* contains a row of orifices or sockets *s*, and the lower flange *a³*, which is preferably wider than the flange *a*, contains two rows of orifices or sockets *s'* and *s²*. The plate *a*, with its socketed flanges, constitutes a holder.

b represent a series of frames made of wire, which is preferably galvanized. Each frame is made of a single piece of wire bent to form two substantially parallel arms 3 4, a cross-bar connecting the outer ends of said arms, and pintles 7 8, formed on the inner ends of the arms. The pintle 7 is preferably elongated and formed to pass through one of the sockets *s* in the upper flange *a²* and one of the inner sockets *s'* in the lower flange *a³*. The pintle 8 is formed to pass through one of the outer sockets *s²* in the flange *a³*.

It will be seen that when the pintles are engaged, as shown, with the holder the arms

project horizontally and are adapted to swing laterally. The upper and lower arms are sufficiently separated from each other to enable each to serve as a clothes-supporter. Hence the device, while reasonably compact in form, has a large holding capacity. It will be observed that the pintles 8 are in front of the line of orifices for the pintles 7. In other words, the pintles of the upper and lower arms 3 and 4 are out of alinement with each other. Owing to this construction the frames, while permitted to swing laterally to some small extent, so as to be sufficiently yielding to prevent breakage thereof, are prevented from swinging to such extent as to rest in contact with each other. In other words, the frames are so mounted as to have a slightly lateral movement and yet have an elastic tendency to resume their relative positions at equal distances apart. The cross-bar 6 serves as a guard to prevent outward displacement of articles hung on the lower arm. The upper arm is preferably bent upward at its outer end to form a guard 5, which prevents outward displacement of articles hung on said arm.

I claim—

1. A clothes-hanger comprising a socketed holder adapted for attachment to a fixed support, and a wire frame bent to form two substantially parallel arms, a bar connecting the outer ends of said arms, and pintles at the inner ends of the arms engaged with sockets in the holder, the said pintles being out of alinement with each other.

2. A clothes-hanger comprising a socketed holder adapted for attachment to a fixed support, and a wire frame bent to form two substantially parallel arms, a guard at the outer end of the upper arm, a bar connecting the said guard with the outer end of the lower arm, and pintles at the inner ends of the arms engaged with sockets in the holder, the said pintles being out of alinement with each other.

3. A clothes-hanger comprising a plate adapted for attachment to a fixed support and provided with an upper flange having a single row of sockets and a lower flange having two rows of sockets and a series of two-armed wire frames, the upper arms having elongated pin-

5 tles extending through the sockets in the upper flange and the inner sockets in the lower flange, while the lower arms have shorter pintles extending through the outer sockets in the lower flange, in front of the said elongated pintles.

In testimony whereof I have signed my

name to this specification, in the presence of two subscribing witnesses, this 23d day of July, A. D. 1897.

ERNEST J. DERAGON.
